UNITED STATES PATENT OFFICE.

CHARLES W. MAYER, OF ROCHESTER, NEW YORK.

COATING-MACHINE.

1,288,641.

Specification of Letters Patent. Patented Dec. 24, 1918.

Application filed March 13, 1917. Serial No. 154,441.

To all whom it may concern:

Be it known that I, CHARLES W. MAYER, a citizen of the United States, residing at Rochester, in the county of Monroe and 5 State of New York, have invented a certain new and useful Coating-Machine, of which the following is a specification.

My invention relates to coating machines for coating or impregnating paper or other 10 fabric with any desired kind of coating requiring the application of heat. It is also an improvement upon the invention of my former Patent, No. 1,043,021, dated October 29, 1912. It is furthermore, a machine 15 adapted to produce either a single, thin coating, double coating, that is, coating on both sides, or producing full impregnation and all intermediate degrees of coating or im- 20 pregnating, and is adapted to papers vary- 25 ing from light weight to the heaviest paper capable of being carried around the rolls and coated or impregnated.

The several objects of my invention will be evident to those skilled in the art from 25 the following specification, claims and drawings, but I state the following main ones;

First, to render the machine capable of producing a substantially full impregnation on very heavy paper; and here it is to be 30 stated that the machine is of such range that it will coat light weight paper with a very small amount of coating to the ream, and thence up to impregnating very heavy paper with an amount of material substan- 35 tially equal to the weight of the paper itself, or coat or partially impregnate papers of the heaviest weight.

Second, to improve the adjustment and control with reference to the coating or im- 40 pregnating.

Third, to improve the draft and chilling means, and thereby increase the speed and efficiency of operation, and by this is meant that I at least double the speed of operation 45 of the machine of my said former patent.

Fourth, to facilitate the threading of the paper into the machine.

It is to be understood that my improve- 50 ment is adaptable to coating webs or fabrics other than paper, and it is to be understood that wherever the term "paper" is used in this connection, it is inclusive of such other uses.

In connection with the objects stated there 55 are certain conditions imposed by physical laws which must be understood in order to

apprehend the nature and purpose of certain of my improvements, and I mention these:

First, as clearly shown in my said Patent No. 1,043,021, in coating paper, as distinguished from impregnating it, neither paper nor coating should be permitted to be affected physically to any appreciable degree from the time the coating is applied until it is chilled and set, or properly spread upon 60 the surface of the paper by a finishing roll, because (and this is the physical law) heated wax or coating once applied and permitted to chill or cool to any appreciable degree before the final operation, never can be re-heated or re-liquefied to return it to the 65 condition when applied. This law applies whether the coating is to be given a gloss by chilling, or a dead finish by annealing.

Second, in making an impregnated or a 70 double coated paper, a certain, definite, and also limited amount of time must elapse between the final application of wax or coating and the final chilling or setting.

Third, in the final chilling or setting of 80 double-coated or impregnated paper, the chilling or final setting from the second surface must immediately follow that of the first,—otherwise one side of the paper will have a good finish, while the other side will 85 have a poor finish. Moreover, this chilling must be done quickly and completely before the paper goes to the wind-up roll.

Referring to the drawings herewith, Figure 1 is a diagrammatic side view of my ma- 90 chine. Fig. 2 is an enlarged sectional detail of the first coating mechanism and impregnating mechanism. Fig. 3 is a detail plan view of the parts shown in Fig. 2, certain parts being omitted for clearness. Fig. 4 95 is a sectional diagrammatic view similar to Fig. 2 showing the parts in position for applying a light coat of wax or other coating.

I will first indicate the main parts of the machine and show the path or run of the 100 paper when impregnation is being effected. Referring especially to Fig. 1, the supply roll of paper, 1, is carried on a mandrel resting in adjustable bearings upon the frame of the machine. The paper thence passes over an idler 2 and under an adjustable and submersible idler 3, thence over the coating roll 4, which rotates in a pan 15 containing the coating, kept hot in the usual manner, thence over the equalizer 5, which evens out and 105 scrapes off the surplus coating, thence over a finishing roll 6, thence over a second coat-

ing roll 7, which applies heated coating substantially the same as the roll 4, thence the paper coated on the second side goes over the equalizer 24, which performs the same function as the equalizer 5, thence the paper coated on both sides or impregnated travels a long distance,—some seven feet in actual construction—free from other than air contact, to permit the coating to reach the proper condition for chilling, that is to say, to permit the physical distribution of the coating in connection with the fiber of the paper which requires a certain amount of time, thence over and about the very large chilling and drawing rolls 9 and 10, and finally to a friction-driven wind-up roll 11. It will be understood that the rolls 4, 6, 7, 9, and 10 are all positively driven from a common source of power in the well-known manner. It will also be understood that the friction wind-up roll 11 is power driven, and that an interposed friction drive, such as shown in my said Patent No. 1,043,021, compensates the increase in diameter and by its adjusting means the pull upon the paper as wound upon it.

It will also be understood that the coating roll 4 is always heated by steam or hot water connections; that the pan in which it revolves is also always heated; that the roll 6 is heated if it is desired to double-coat or anneal or impregnate the paper, but is cooled with cold water if a gloss finish is desired in making coated paper; that for double-coating or impregnation the roll 7 and pan 8 are heated, but that for single coating the roll 7 is run cold and without coating in the pan 8. The rolls 9 and 10 are always run cold and kept cold by water circulation.

I will now describe the mechanism and operation when the machine is used to impregnate paper. Mounted on lugs 12 secured to the frame of the machine are guides 13, within which rack-toothed bars 14 are vertically movable. Pivoted near the lower ends of these bars is the submersible roll or idler 3. The bars 14 are so positioned that they are adjustable inside the coating pan 15 near its ends. Pivoted to the lugs 12, or journaled therein, is a shaft 16 which has rigidly mounted upon it the pinions 17, in mesh with the racks of the bars 14, and the shaft 16 is provided with a crank 18 by which it may be rotated, and also with a clamp 19 (see Fig. 3) by which it may be locked in any desired position. It will thus be seen that, by the parts just described, the submersible roll 3 may be moved in a vertical plane, parallel to the axis of the coating roll 4 and close to its surface, the purposes and advantages of which will hereafter more fully appear. In this position the submersible idler or roll 3, where it is below the level of the coating (for it is, of course, understood that the coating pan 15 is filled sufficiently for the

under side of the coating roll 4 to contact with and carry up the coating on its surface), the liquefied coating not only contacts and coats the paper upon its under side, but the coating flows in at the two ends of the loop of the paper looped under the idler 3 and coats the upper side of the paper as well. And it is also to be noted that, having the paper travel down and up in this manner in close proximity to the coating roll 4, the paper itself is thoroughly heated, so that the capillary action carrying the coating into the fiber of the paper is much more complete, because a very slight cooling of the coating by thick, cold paper materially reduces the free distribution of the coating into the fiber of the paper.

With this position of operation it is necessary to remove the surplus coating upon the upper side of the paper, and this is accomplished by the following means: Pivoted to the plates 14 is a bar 20 (see Fig. 2), and to this bar is secured a scraper 21, which is a plate having its lower edge bearing against the face of the web as it passes from the roll 3 to the roll 4. This scraper is adjustable, either to cause it to act more or less upon the web or to move it entirely out of contact when its use is to be dispensed with, by means of an arm 22 provided with a slotted segment which can be locked to the adjacent bar 14 by means of a bolt and wing-nut. The paper passing over the coating roll 4 is, in this position, in contact with nearly one-third of its periphery and receives thorough saturation due to the heat of the roll and the coating carried by it. As it passes over the equalizer 5 the surplus coating is removed. The roll 6, being heated, tends to drive the coating into the paper; and when the paper reaches the roll 7, which takes heated coating from the pan 23, it is further charged with coating on the side opposite to that applied by the roll 4, and the equalizer 24 removes the surplus.

In case the coating or impregnation has been sufficient by the rolls 3 and 4, the coating pan 23 may be empty, the roll 7 heated, and the equalizer 24 will smooth out any coating pulled up as the paper passes over the rolls 6 and 7.

By these treatments the paper is not only thoroughly coated on both sides, but the heating has driven the coating well into the paper; and yet, if it were now and at once subjected to the action of the chilling rolls, the coating or impregnation would not be entirely uniform. This fact I have demonstrated repeatedly, and I have found that between the last treatment of coating or heating and the first action of chilling, a positive, definite time element must enter in, as above stated, secured by placing the chilling rolls a very considerable distance from the equalizer 24. This distance must be approxi-

5 mately seven feet with a web traveling at the speed of five hundred feet for minute. Small as is this period with a web running at such speed, it is essential to the best results; and I believe myself to be the first to have discovered this fact and to have determined the extent of such time element with sufficient accuracy to enable others to employ the same.

10 Directly connected with this feature of my invention is my improvement in the cooling or chilling means. The rolls 9 and 10 (see Fig. 1) are both drawing rolls, drawing the web through the machine, and are also 15 the cooling or chilling rolls. They are much larger in diameter than any of the other rolls, and preferably travel at the same peripheral speed as the roll 6. They have thin walls and are fully supplied with cold water 20 circulation, so as to absorb substantially all of the heat which the rolls pick up from the coated or impregnated paper substantially as fast as the same is picked up. As shown, 25 the paper contacts a little more than one-half the periphery of the roll 9, and then makes nearly an equal contact with the roll 10. This gives a much longer contact for chilling the coating, and these rolls being 30 very large, the period of non-contact is similarly increased, so that the water has a very much greater effect in removing the heat 35 from the rolls. And it is also important, as already stated, that the action of the roll 10 shall follow immediately the action of roll 9, in order to secure equally good finish to both sides of the paper.

Going now to the other extreme of adaptability of my invention, assume that it is desired to coat (not impregnate) a paper upon 40 one side only and with the smallest amount of coating possible to secure an even and complete covering. The clamp 19 is released so that the crank 18 may be turned, and through the pinions 16 and the racks on 45 the bars 14, the bars 14 are raised, bringing the roll 3 to the position shown in Fig. 4. In this position the paper between the roll 3 and the equalizer 5 makes a very small contact with the coating roll 4, receiving the 50 minimum amount of coating and reducing the amount of saturation or impregnation to the negligible point. The equalizer 5 acts as above described, and if it is desired to make a dead finish paper, the roll 6 is run 55 hot; but if it is desired to make a high finish or glaze, the roll 6 is supplied with a cooling medium. The interchangeable use of a heating medium or a cooling medium in a given roll is well known and fully disclosed 60 in my said former patent. Leaving the roll 6 the paper contacts the roll 7, which may

be either hot or cold, the same as roll 6; but the equalizer 24 is moved down out of contact with the paper. The paper then passes to the chilling rolls 9 and 10, as above described, and finally to the wind-up roll 11.

65 Between these extremes—full impregnation of a very heavy paper and a very light, single coating of light paper—lie all of the modifications of impregnation, single coating, double coating, made possible by having the roll 3 adjustable in vertical plane and close to the roll 4, and the other means above described. I am aware that submerged rolls 70 for carrying a web down into the coating have been used, but to my knowledge none of these has been adjustable to attain the ends which I have described. Moreover, it must be had in mind that my invention 75 adapts the machine to such speeds as I have 80 stated, while the prior machines just referred to operated at a speed of not more than seventy-five feet per minute.

Finally it is to be noted that this invention 85 embraces an improvement in threading the machine. When it is desired to thread in the end of a roll of paper, the roll 3 is elevated to the position shown in Fig. 4, and the paper is readily passed over the idler 2, under the roll 3, over the coating roll 4, and 90 so on; and then the roll 3 is lowered to the desired position.

Having thus described my invention, I claim:

1. In a machine of the type described, the 95 combination with means for carrying a web through the machine, and a coating roll, of a vertically movable frame, an idler carried by said frame adjacent said coating roll, and a scraper adjustably mounted on the frame 100 to remove the surplus coating from the upper side of the web after it passes under said idler.

2. In a machine of the type described, the 105 combination with means for carrying a web through the machine, an idler, a coating roll and coating pan in which said coating roll rotates, of a submersible and adjustable roll 110 vertically adjustable in a plane adjacent said coating roll, rack-toothed plates to which said adjustable roll is pivoted, guides for said plates, pinions engaging said teeth and means for rotating said pinions, a scraper 115 for removing the surplus coating from the upper side of the paper after it passes under said submersible roll, a bar pivoted to said plates and carrying said scraper and an arm and slotted segment for adjusting said scraper and for throwing it out of contact with said web when desired.

CHARLES W. MAYER.
